UNITED STATES PATENT OFFICE.

NATHAN H. SUREN, OF NEEDHAM, MASSACHUSETTS, ASSIGNOR TO THE GAMEWELL FIRE-ALARM TELEGRAPH COMPANY, OF NEW YORK, N. Y., A CORPORATION OF NEW YORK.

ELECTRIC-SIGNAL RECORDER.

938,286.

Specification of Letters Patent. Patented Oct. 26, 1909.

Application filed May 14, 1909. Serial No. 495,963.

To all whom it may concern:

Be it known that I, NATHAN H. SUREN, of Needham, county of Norfolk, State of Massachusetts, have invented an Improvement in Electric-Signal Recorders, of which the following is a specification.

This invention relates to electric-signal recorders for recording fire-alarm, police and other signals on a recording-tape.

The invention has for its object to construct a recorder including means for cutting slots of varying length in the recording-tape. Also to construct a recorder including a marker adapted to cut slots of varying length in the recording-tape by means of a continuous cutting action, as for instance, by a shearing action. Also to construct a recorder including a slotting-tool adapted to slot the recording-tape, and means to operate said tool and hold it in engagement with the tape for different lengths of time, whereby slots of varying lengths may be produced in said tape. Also to construct a recorder inclosing means for cutting slots of varying lengths in the recording-tape and forming tongues. Also to construct a recorder including a marker adapted to slot the recording-tape to form a tongue and to sever the tongue thus formed. Also to construct a recorder including a marker adapted to cut slots in the recording-tape and form successive tongues and respectively sever them to produce slots of varying length. Also to construct a recorder with a movable-carrier and a segmental slotting-tool pivoted thereto, and means to operate said carrier to force the slotting-tool through the recording-tape and form a slot therein. Also to provide for movement of said segmental slotting-tool by and in unison with the recording-tape. Also to construct a recorder including a slotting-tool for the recording-tape having one or more cutting teeth, as for instance, it may have an initial cutting-tool, or both an initial and a final cutting-tooth, or it may have in addition to said cutting-teeth, one or more cutting-teeth arranged at intervals therebetween, which are successively apertured to form open slots in the tape.

The invention also has for its object to construct a recorder in which the recording-tape is adapted to be moved at a uniform speed during the recording of a signal, hav-

ing in combination, a slotter, intermittently movable, to intersect the path of movement of the tape and to effect penetration thereof by its leading edge which is also movable in unison with the tape after such penetration to cause successive portions thereof to engage and cut a slot in said tape, and means to determine the duration of engagement of the slotter with the tape to thereby regulate the length of the slot.

Figure 1 is a side elevation of a sufficient portion of a recorder to illustrate my invention, the parts being in their normal positions. Fig. 2 is a detail of the slotting-tool in engagement with the tape at the beginning of its movement. Fig. 3 is a detail of the slotting-tool in engagement with the tape at the end of its movement. Fig. 4 is an end view of the slotting-tool and carrier therefor and grooved tape-support. Fig. 5 is a plan view showing a plurality of slotting-tools. Figs. 6, 7, 8 and 9 are details of modified forms of slotting-tools. Fig. 10 is a detail of a portion of the recording-tape which has been slotted by a slotting-tool embodying this invention.

The recorder herein shown for the purpose of illustrating my invention is of the multiple-pen variety, it being arranged with four circuits, but it may be arranged for any other number of circuits or for a single circuit. The receiving electro-magnet a , of any one of the circuits, see Fig. 1, is supported by a stand a' . Its armature a^2 is pivoted at a^3 , and has an arm a^4 , adjustably or otherwise connected by a link a^5 with the upper end of an actuating-lever b . Said actuating-lever is pivoted at b' , and extends downward, and its lower end is arranged to engage a carrier d , it being preferably provided at its extremity with a roll b^2 which engages the carrier. The carrier d , is here shown, as an arm pivoted at d' , and adapted to bear at its extremity a slotting-tool or marker for the recording-tape. Said arm d has an inclined portion or cam d^2 , which is engaged by the actuating-lever, so that when said actuating-lever is moved on its pivot it will act to depress the arm d . Said arm d is restored to its normal or elevated position by a spring d^3 when the actuating-lever b resumes its normal position. The actuating-lever also has at its lower end an extension

*b*³, which is adapted to operate to release a train, not shown, for moving forward the recording-tape, said train and the releasing-mechanism therefor being of any well known or suitable construction, as for instance, I may employ the train represented in the recorder shown in my application for Letters Patent #458,042 filed October 16, 1908. Said train is adapted to rotate the lower feed-wheel *g'* for the tape, with which operates an upper feed-wheel *g*, to move the tape positively and at a uniform speed. The slotting-member or tool, herein also termed the "marker," for slotting the recording-tape, is here shown as pivoted to the extremity of the arm *d* and is held by said arm above the path of movement of the recording-tape, see Fig. 1. Depression of the arm *d* acts to move the slotter into engagement with the tape, to puncture and slot the same, and as such depression is due to the operation of the armature of the electro-magnet *a*, the length of time the slotter remains in engagement with the tape will be dependent upon the duration of the period during which said electro-magnet is continuously energized. If the armature is vibrated quickly the slotter will be operated to cut short slots in the tape, representing the conventional dots of a signal, and if the vibrations of said armature are of long duration, then the slotter will be operated to cut long slots, representing the conventional dashes of a signal.

35 The slotter here shown in Figs. 1 to 6, is segmental in shape, and made as a thin metal plate, its body *c* being pivoted at its upper corner, at *c'*, to the arm *d*, and said body having a stop-pin *c*² normally held against the arm by means of a light spring *c*³, attached at one end to the arm and at the other end to the pivot-shaft of the slotter. The lower corner of the slotter is prolonged to form a pointed penetrating tooth *c*⁴, and the rear or lower edge *c*⁵ of the body is made as a circular arc extending from the tooth *c*⁴ to the upper edge and struck from the pivot *c'*, as a center, and of such radius that when the armature is attracted the curved edge *c*⁵ will continuously intersect and pass across the plane of the recording-tape, if the slotter is swung on its pivot *c'* until it reaches the end of its curved edge. The segmental slotter in addition to having the tooth *c*⁴, which serves as an initial cutting-tooth, also has other like cutting-teeth, herein shown as *c*⁶, *c*⁷, *c*⁸. The cutting-tooth *c*⁸ is arranged at the extreme rear end of the curved edge of the segment and the cutting-teeth *c*⁶ and *c*⁷ are arranged at intervals between said teeth *c*⁴ and *c*⁸. Beneath the slotter a support for the tape *h* is arranged, here shown as a rotatable roll *e* having an annular groove *e'* therein, made slightly wider than the trans-

verse thickness of the cutting-teeth and of the plate *c* bearing said teeth, and of such depth that the teeth will clear the bottom of the groove when the slotter is in its lowermost position. When said slotter enters the groove in said roll the tape is cut by it with a continuous shearing action, the edges of the slotter coöperating with the sides of the groove in the supporting-roll for the accomplishment of this result. When a signal is received the recording-train moves forward the recording-tape at a uniform speed, and the carrier *d* is moved to move the slotting-member toward and into engagement with the tape, the initial cutting-tooth penetrating the tape and passing into the groove in the supporting-roll *e*, see Fig. 2. It will be seen that the tip of the initial tooth at such time is a slight distance behind or at the right of the center of the grooved roller. When the tooth penetrates the tape a short slot or perforation is made, and if the signal impulse is short the magnet is immediately deenergized and the slotting-member is immediately returned to normal, the cutting-tooth being withdrawn entirely from the tape. When the initial tooth penetrates the tape the feeding-movement of the tape, acting upon the rear edge of said tooth and the lower edge of the slotter causes the slotter to swing on its pivot, moving in unison to the tape. With a short signal impulse the movement of the slotter in unison with the tape and relative to its carrier is very short, but during the time the tooth penetrates the tape the edge of the slotter which has also crossed the plane of the tape acts to cut a short piece or tongue from the strip, the edge of the slotter acting in conjunction with the sides of the groove in the supporting-roll to make two parallel shear cuts in the tape extending from the point of penetration rearward to the point at which the slotter disengages the tape.

If the slotter is provided with a cutting-tooth *c*⁶ then said tooth will also penetrate the recording-tape at the end of the short signal-impulse and sever the tongue thus formed, but if the slotter is devoid of said tooth, as shown in Fig. 6, the tongue thus formed will not be severed. Or, if the slotter should be withdrawn from the tape before the tooth *c*⁶ arrives in position to sever the tongue, then said tongue will not be severed from the tape. The particular advantage gained by not severing the tongues from the tape is that after the tape has passed between the feed-wheels *g* and *g'* and said tongues thereby turned backward on the tape and the tape has been detached from the recorder they will serve to indicate the correct direction for reading the signal. In some instances, however, this advantage is not deemed to be of sufficient importance to

warrant leaving the tongues on the tape, and hence they are severed therefrom. My invention, however, is designed to comprehend construction by which either result may be accomplished.

If the signal-impulse is of long duration the angular movement on the slotter relative to its carrier will be correspondingly greater, and a greater portion of the edge of the slotter will move across the plane of the tape, the latter being acted upon by successive parts of said edge, so that a long slot will be cut in the tape, and in such case the cutting-teeth c^6 , c^7 , c^8 , will penetrate the tape and will act successively to sever the tongues previously formed. The length of the signal-impulse will determine the length of the slot and consequently determine which cutting-tooth will act as the final cutting-tooth. For short slots the second cutting-tooth c^6 will be the final cutting-tooth, for longer slots the third cutting-tooth c^7 will be the final cutting-tooth, and so on. The small pieces removed from the tape by means of a slotting-tool may cling to the grooved supporting-roll, and to clear said roll of said pieces a finger f is provided, the end of which extends into the groove of the roll, see Fig. 1, and preferably bottoms therein, and acts to divert the smaller pieces, causing them to fall away from the supporting-roll. The initial cutting-tooth c^4 on the segmental-plate may be omitted, see Fig. 9, and the other cutting teeth employed, and in such case the tongue or tongues will be produced and severed.

The cutting-teeth may be entirely omitted, and still slots of varying length formed in the recording-tape by a continuous cutting action, as represented in Fig. 7, wherein it will be seen that a circular slotting-disk i is shown, adapted to enter the groove in the roll e . Furthermore, instead of making the slotting-member or marker as a segmental plate having one or more cutting-teeth on its edge, it may be made as a circular-disk j , see Fig. 8, having a large number of cutting-teeth on its edge. By means of said disk a slot will be continuously formed in the tape as long as the disk is held in engagement with it. Various other changes and modifications and details of construction and arrangement may be made by those skilled in the art without departing from the spirit and scope of my invention, as set forth in the claims annexed hereto.

Having thus described my invention, what I claim as new and desire to secure by Letters Patent is:

1. A recorder having a marker adapted to slot the recording-tape to form a tongue and having means for severing the tongue thus formed, substantially as described.

2. A recorder having a marker adapted to

cut slots of varying lengths in the recording-tape to form tongues and having means for severing the tongues thus formed, substantially as described.

3. A recorder including a marker adapted to slot the recording-tape to form a tongue and to sever the tongue thus formed, and means to operate said marker, substantially as described.

4. A recorder including a shearing marker adapted to slot the recording-tape to form a tongue and to sever the tongue thus formed, and means to operate said marker, substantially as described.

5. A recorder including a pivoted marker adapted to cut slots in the recording-tape to form a tongue and to sever the tongue thus formed, and means to operate said marker, substantially as described.

6. A recorder including a marker adapted to form slots in the recording-tape by means of a continuous cutting action and thereby form tongues and to sever the tongues thus formed, and means to operate said marker, substantially as described.

7. A recorder including a marker adapted to cut slots of varying lengths in the recording-tape by means of a continuous cutting action and form tongues, and to sever the tongues thus formed, and means to operate said marker, substantially as described.

8. A recorder including a shearing marker adapted to cut slots of varying length in the recording-tape by means of a continuous shearing action and form tongues and to sever the tongues thus formed and means to operate said marker, substantially as described.

9. A recorder including a pivoted marker adapted to cut slots in the recording-tape of varying length and form tongues and to sever the tongues thus formed, and means to operate said marker, substantially as described.

10. A recorder including a marker adapted to cut a long slot in the recording-tape and form a plurality of tongues, and to sever the tongues thus formed, and means to operate said marker, substantially as described.

11. A recorder including a slotting-tool adapted to cut slots in the recording-tape having an initial cutting-tooth and a final cutting-tooth, substantially as described.

12. A recorder including a slotting-tool adapted to cut slots in the recording-tape and having a plurality of cutting-teeth, substantially as described.

13. A recorder including a slotting-tool adapted to cut slots in the recording-tape having an initial cutting-tooth and a final cutting-tooth and one or more intermediate cutting teeth, substantially as described.

14. A recorder including a shearing

- marker having a curved shearing portion and a plurality of transversely arranged cutting-teeth thereon, substantially as described.
- 5 15. A recorder including a shearing marker having a curved shearing portion, an initial cutting-tooth and final cutting-tooth, and one or more cutting-teeth therebetween, substantially as described.
- 10 16. A recorder including a pivoted segmental marker having an initial cutting-tooth and a final cutting-tooth, substantially as described.
17. A recorder including a pivoted segmental marker having an initial cutting-tooth, final cutting-teeth, and one or more cutting-teeth therebetween, substantially as described.
18. A recorder including a shearing marker adapted to form slots in the recording-tape, a grooved supporting-roll with which it coöperates, and means, as a finger, for clearing the supporting-roll of the pieces removed from the tape, substantially as described.
- In testimony whereof, I have signed my name to this specification, in the presence of two subscribing witnesses.

NATHAN H. SUREN.
